PHOTOENGRAVING PROCESS

James Henry Gibson, Teaneck, N. J.

Application September 22, 1936, Serial No. 101,921

1 Claim. (Cl. 101—401.3)

This invention relates to a photo-engraving process, an object of the invention being to provide a process which will result in the making of a printing plate which when used in printing accentuates the high lights of a picture or reproduction made therefrom.

The invention, therefore, consists in certain novel steps in the process all of which will be more fully hereinafter described and pointed out in the claims.

In the accompanying drawing—

Figure 1 is a fragmentary plan view illustrating one step of my improved process;

Fig. 2 is a similar view illustrating the next 15 step in the process;

Fig. 3 is a view in section on the line 3—3 of Fig. 1;

Fig. 4 is a view in section on the line 4—4 of Fig. 2;

Fig. 5 is a fragmentary view in section on an 20 enlarged scale illustrating the printing plate after it has been developed and etched; and

Fig. 6 is a view similar to Fig. 5 illustrating the plate after it has been subjected to pressure 25 of a mat thereon.

The first step of my improved process is to provide a printing plate of suitable metal coated on both surfaces with a sensitized solution. This plate is indicated by the reference character 1 30 and the sensitized solutions on opposite surfaces thereof are given the reference character 2. For convenience of description the printing surface of the printing plate will be hereinafter referred to as the top surface and the other surface of 35 the printing plate will be hereinafter referred to as the back surface of the plate.

On both the top and back surfaces of the printing plate an image is transferred from an ordinary thin glass plate 3, the images on the opposite sides of the printing plate being in exact register. For convenience of description we will assume that the surface of the glass plate 3 containing the half-tone negative 4, is the front surface and the other surface the back surface 45 of the said plate.

This transfer of the image to both surfaces of the printing plate is accomplished as follows:

The sensitized top or printing surface of the printing plate 1 is located directly against the 50 half-tone negative 4 on the front surface of the glass plate 3, and both plates are aligned at least two edges and are clamped in an ordinary printing frame 5 and exposed to light in the ordinary way to transfer the image to the sensitized 55 printing surface of the printing plate. This step

of the process is illustrated in Figs. 1 and 3 of the drawing.

The printing plate 1 and the glass plate 3 are then reversed with the sensitized back of the printing plate located directly against the back of the glass plate, and the half-tone negative now substantially remote from said back of the printing plate. While thus arranged the plates have the same edges registered as before and are again secured in the printing frame 5 and exposed in the ordinary way. As seen in Figs. 3 and 4 the glass plate or other transparency 3 is of substantial thickness, this being an essential factor in this particular step of the process because it is by this second exposure of the printing plate through the reversed glass plate of reversed thickness that the half-tone dots in the intermediate tones and shadows are merged into solids which, later, become the bolsters or supports of the intermediate tones and shadows of the printing surface. It is also during this transfer that the high light dots are virtually eliminated because of the diffusion of the light rays through excessively thick transparency. This step of the process is illustrated in Figs. 2 and 4 of the drawing and results in transferring the image to the sensitized back surface of the printing plate. We then have a printing plate with the images on both sides thereof in exact register.

The printing plate 1 is then developed, simultaneously developing the images on both sides of the plate which are, as above stated, in exact register. The printing surface of the metal plate which was subjected to direct contact with the negative, gives a half-tone screen over the entire image that will be used to print from.

After the plate has been developed the next step is to etch both sides of the plate by subjecting the same to a bath of suitable acid as is common in the art. When my improved plate is subjected to this etching process, the result will be to provide on the printing surface of the plate at the high lights of the image a large number of points 6. This is the surface of the plate which has been subjected to direct contact with the negative. The other surface, which is referred to as the back surface of the printing plate, is substantially free from these points. This is due to the fact that in carrying out the step of the process shown in Figs. 2 and 4 of the drawing the light rays can pass through the negative at various angles causing the screen to practically disappear over the entire area, and when this back surface is etched the result will be that the high light portions of the image on

the back surface of the plate are cut away or recessed as shown at 1. The plate thus developed and etched is illustrated in Fig. 5 of the drawing.

The printing plate is then subjected to the pressure of a mat thereon, which is a step in the ordinary printing process. When the plate is subjected to this or other pressure these portions of the plate containing the high lights of the image, indicated at 6 on the drawing, are forced downwardly below the surfaces of the dark or shadow portions of the image leaving the plate as indicated in Fig. 6 of the drawing.

Thus when the printing is done the darker areas as well as the lighter areas are accentuated. This gives a very much improved result in the reproduction of images and is an economical process as compared with other processes heretofore known and designed for a like purpose.

I claim:

20 A photo-engraving process comprising sen-

sitizing both surfaces of a metal printing plate producing a half-tone negative on the obverse side of a transparency of substantial thickness, contacting one of the surfaces of said sensitized plate with the obverse side of said transparency so as to bring said negative into direct contact with said one surface of said plate, exposing the contacted transparency and plate to the action of light, contacting the other side of said sensitized plate with the reverse side of said transparency; again subjecting said plate and transparency to the action of light, the substantial remoteness of the half-tone negative from said second side of the plate causing such diffusion that the screen gradations in the intermediate tones and shadows merge into solids and the high light dots virtually disappear, then developing and etching the plate.

JAMES HENRY GIBSON.
